UNITED STATES PATENT OFFICE

2,470,758

DISTRIBUTION OF MANIFEST SHEETS

Clem Bursett, Seattle, Wash.

Application July 3, 1946, Serial No. 681,266

5 Claims. (Cl. 211—134)

(Granted under the act of March 3, 1883, as
amended April 30, 1928; 370 O. G. 757.)

1

This invention relates to a distributing apparatus and more particularly to an apparatus for distributing sheet material or the like.

An object of the invention is to provide such an apparatus with which sheet material such as manifest sheets or the like can be quickly and efficiently distributed.

Another object of the invention is to provide such a distributing apparatus with which sheet material can be readily distributed with utilization of a minimum of time and space.

A further object is to provide a device by which sheet or other material can be distributed readily and accurately, which is simple in construction, simple to operate, and which can be economically manufactured.

In the drawings:

Fig. 1 is a perspective view in elevation of an assembly embodying the invention.

Fig. 2 is a side elevation of a detail.

Fig. 3 is a top plan view of the detail shown in Fig. 2.

Fig. 4 is a fragmentary elevation showing a detail.

Fig. 5 is a perspective view of a portion of a single column cabinet embodying the invention, on a larger scale than Fig. 1.

In the handling of manifest sheets or the like, as at ship loading docks or freight loading depots large numbers of manifests are made. These manifests must be distributed to separate piles so that the piles will be alike and have the proper number of like and different sheets. In the past counter space has been employed and the stacking or distributing done by hand from stack to stack. With the utilization of the apparatus of the present invention, valuable counter space is saved; the sheets can be left in the device indefinitely whereas the counter, if used, must be cleared at the close of daily operations. The apparatus of this invention also saves much time as it eliminates moving from pile to pile on the counter; and also with but a flip of the finger the sheet falls into its proper place within the cabinet. With this device the work can be done in about one fourth of the time taken by prior methods.

The apparatus comprises a cabinet or housing of any desired size and may be constructed of any suitable material. The cabinet or housing preferably comprises a back wall 1 and a top 1a, and a desired number of vertical walls 2. Between the vertical walls there are suitably mounted, as by nails or other securing means, not shown, a desired number of shelves 3, hav-

2

ing any desired vertical spacing. The shelves are preferably inclined downwardly from the front to the rear of the cabinet. The shelves 3 are slightly smaller in fore and after dimension than the housing or cabinet so that when mounted within the cabinet their front edges will not extend to the front of the cabinet, thus leaving a space as indicated at 10. Facing members 4 are preferably affixed to the front of the vertical housing walls 2 and are desirably disposed to slightly overlap the forward edge of the shelves 3, and are spaced therefrom as seen at 10. Notches or openings 5 are formed in the facing strips 4 at points intermediate the space between the various shelves. Above each notch 5 there is affixed an inwardly extending member 6, which may desirably be an angle iron having its inwardly extending portion substantially parallel to the overlying shelf and preferably extending under the shelf, as seen in Fig. 4. The other portion 6a of the angle iron is suitably affixed to the facing member 4, as by screws or the like 6b. The embodiment also includes means for distributing sheet material or the like to the shelves, comprising a feeder or distributing tray, desirably comprising a rectangular bottom or base plate 7. The base plate has a narrowed portion 7a at one end thereof. Side members 8, each having a longitudinal groove 8a extending throughout its length, are affixed to the base plate or bottom 7 by glue or other suitable means, the base plate being received in the grooves in the side members to the point of commencement of the narrowed portion 7a as shown at 7b. The side members are desirably shorter than the base plate at the narrowed end of the base plate 7a and are each provided near this end with a suitable hole or opening 8b extending transversely from the groove 8a. A hook member 9 having outwardly bent portions 9a and 9b at opposite ends thereof is preferably provided at each side of the tray, each hook member 9 being positioned in the groove 8a of the respective side member 8 with the outwardly bent portion 9a received in the hole 8b of the side member 8. The hook member 9 is held firmly in the groove 8a by the side of the narrowed portion 7a of the base plate. The longitudinally projecting portion of the hook member 9 having the outwardly bent portion 9b extends desirably to the end of the narrowed portion 7a of the base plate 7. The distance from the end of the side member 8 to the outwardly projecting portion 9b of the hook member 9 is desirably slightly greater than the distance

from the outer surface of the facing strip 4 of the cabinet to the innermost extension of the angle iron 6 in the cabinet. The hook members 9b are of such size and are so positioned as to be adapted to pass through the notches 5 in the facing strips 4, and to pass vertically through the spaces 10 between the facing strips and the forward edges of the shelves. The overall width of the base plate extension 1a of the tray together with the longitudinally disposed stems of the hooks 9, disposed at either side thereof, is desirably slightly less than the width of the aperture between the facing strips on the cabinet, thus providing for free movement of this portion of the tray therein. The ends of the upstanding side members 8 of the tray are adapted to abut the facing strips 4 on the outer face thereof to prevent the tray from sliding too far within the housing.

In operation, the feeder tray carrying the material to be distributed is manually inserted with its hooks 9b passing through any desired set of notches 5 in the facing strip 4. The tray is then allowed to fall until the hooks 9b are caught by the first shelf below the notches through which the hooks were inserted. At this point the base plate of the feeder tray desirably may be held substantially parallel or nearly so with the shelf on which it rests. In any event the outer end of the tray is manually held at a suitable elevation. While in this position the operator can readily manually slip or move the desired material off of the tray and onto the shelf. Then to lower the tray to the next shelf in the column, the operator pulls the tray outwardly thus allowing the outwardly bent portions 9b of the hook members 9 of the tray to clear the outer edge of the shelf and to drop down to be caught by the angle iron 6, thus preventing the tray from slipping by the next shelf. The tray is then pushed inwardly until it clears the innermost end of the angle iron, thus allowing it to fall to rest on the next shelf where desired material is deposited as before.

It is apparent that the invention may be embodied in various forms, and that numerous variations in parts and arrangement of parts may be made, and that the invention is not to be limited to the embodiment shown and described, the scope of the invention being defined in the appended claims.

The invention described herein may be manufactured and used by or for the Government of the United States of America for governmental purposes without the payment of any royalties thereon or therefor.

What is claimed is:

1. In combination in apparatus for the distribution of material, a housing, vertically spaced shelves in said housing, a distributing tray having a portion extending into said housing and adapted to rest on any one of said shelves, said extended portion of said tray including lateral projections, said shelves terminating short of the front of said housing, vertically disposed facing members on the front of said housing opposite the sides of said shelves and spaced from the forward ends of said shelves, said facing members having openings therein at a point above one of said shelves to permit passage therethrough of the lateral projections of said extended portion of said tray into said housing, and said facing members having inwardly extending members extending beneath said shelves, said facing members and inwardly extending members being disposed for engage-

ment with the lateral projections of said extended portion of said tray during movement of said tray from one shelf to another and normally retaining said extended tray portion within said housing during said movement of said tray, said extended portion of said tray including a portion of a width to pass between said facing members.

2. In combination in apparatus for the distribution of material, a housing, vertically spaced shelves in said housing, a distributing tray having a portion extending into said housing and adapted to rest on any one of said shelves, said shelves terminating short of the front of said housing, vertically disposed facing members on the front of said housing opposite the sides of said shelves and spaced from the forward ends of said shelves, said facing members having openings therein at a point above one of said shelves to permit passage of said extended portion of said tray into said housing, and said facing members having inwardly extending members extending beneath said shelves, said facing members and inwardly extending members being disposed for engagement with said extended portion of said tray during movement of said tray from one shelf to another and normally retaining said extended tray portion within said housing during said movement of said tray, said extended portion of said tray including laterally disposed projections adapted to pass through the said openings in said facing members and to be supported selectively on said shelf or on said inwardly extending members.

3. In combination in apparatus for the distribution of material, a housing, vertically spaced shelves in said housing, a distributing tray having a portion extending into said housing and adapted to rest on any one of said shelves, said extended portion of said tray including lateral projections, said shelves terminating short of the front of the housing, vertically disposed facing members on the front of said housing opposite the sides of said shelves and spaced from the forward ends of said shelves, said facing members having openings therein at a point above one of said shelves to permit passage therethrough of the lateral projections of said extended portion of said tray into said housing, and said facing members having inwardly extending members extending beneath and spaced from said shelves and substantially parallel thereto, said facing members and inwardly extending members being disposed for engagement with the lateral projections of said extended portion of said tray during movement of said tray from one shelf to another and normally retaining said extended tray portion within said housing during said movement of said tray, said extended portion of said tray including a portion of a width to pass between said facing members.

4. In combination in apparatus for the distribution of material, a housing, vertically spaced shelves in said housing, a distributing tray having a portion extending into said housing and adapted to rest on any one of said shelves, said shelves terminating short of the front of said housing, vertically disposed facing members on the front of said housing opposite the sides of said shelves and spaced from the forward ends of said shelves, said facing members having openings therein at a point above one of said shelves to permit passage of said extended portion of said tray into said housing, and said facing members having inwardly extending members extending beneath said shelves, said facing members and inwardly extending members being disposed for engage-

ment with said extended portion of said tray during movement of said tray from one shelf to another and normally retaining said extended tray portion within said housing during said movement of said tray, said tray comprising a base plate, side members adapted to receive said base plate for a portion of their length, hook members affixed in said side members, and providing lateral projections, said hook members being retained in position by a portion of said base plate.

5. In combination in apparatus according to claim 4, the ends of said side members being spaced from the lateral projections, said ends providing abutments to engage said facing members to limit movement of said tray inwardly of said housing.
